CLAIM

We claim the ornamental design for a runner for ice skate, as shown and described.

DESCRIPTION

FIG. 1 is a side environmental view of a runner for ice skate according to our new design;

FIG. 2 is a tridimensional view of the runner for ice skate in accordance with our new design;

FIG. 3 is a top plan view of the design of FIG. 2;

FIG. 4 is a bottom plan view of the design of FIG. 2;

FIG. 5 is a side elevation view of the design of FIG. 2, the opposite side being a mirror image thereof;

FIG. 6 is a front elevation view of the design of FIG. 2; and,

FIG. 7 is a rear elevation view of the design of FIG. 2.

The broken lines represent the environment in which the article resides and forms no part of the claimed design.
